PLAYER ACTION COMPANY, OF DEEP RIVER, CONNECTICUT, A CORPORATION OF
CONNECTICUT.

PLAYER-PIANO.

1,384,993.

Specification of Letters Patent. Patented July 19, 1921.

Original application filed April 24, 1918, Serial No. 230,417. Divided and this application filed August 4, 1919. Serial No. 315,208.

To all whom it may concern:

Be it known that I, STANLEY L. FISHER, a subject of the King of Great Britain, residing in Chester, county of Middlesex, 5 State of Connecticut, have invented certain new and useful Improvements in Player-Pianos, of which the following is a full, clear, and exact description.

This invention relates to player pianos and it has more particular reference to pneumatically actuated pianos of the upright type, wherein a so-called "upper action" or chest with its appurtenant valve mechanism and pneumatics for operating the respective 10 units of the piano action proper extends across the front of the piano in the case thereof above the key-board and in front of the piano action, each unit of the player action being properly connected with and 15 adapted to operate the corresponding unit of the piano action. Each piano action unit ordinarily comprises a hammer for striking the string, a pivoted wippen or jack beam, and a hammer jack mounted on the wippen 20 in the customary manner, the wippen being operated to actuate the hammer by a connection with the corresponding player action unit for pneumatic playing, and said wippen being connected with the corresponding 25 key of the piano for playing by hand.

One of the primary objects of my invention is the provision of an improved and simplified player action of the type set forth, which has the advantages of simplicity, 30 compactness, efficiency of operation, ready accessibility for inspection and repairs, and low cost.

A more specific object of the invention is to provide an improved form of connection 35 between the striker pneumatics and the corresponding units of the piano action. By my improvements, the number of parts interposed between each pneumatic and the corresponding piano action unit is cut down 40 to a minimum, and yet provision is made for easy and nice adjustment of the parts, which can be readily carried out when the player action is installed in the piano case,

so that the hammers will strike the strings uniformly.

To these and other ends, the invention consists in the novel features and combinations of parts to be hereinafter described and claimed.

In the accompanying drawings:

Figure 1 is a diagrammatic, vertical transverse section through the upper portion of a player piano embodying my improvements, showing the main parts of one of the piano action units and the wind chest, 60 valve mechanism and striker pneumatics of the player action;

Fig. 2 is a rear elevation of one end portion of the pneumatic action as the same would appear detached from the piano;

Fig. 3 is a top plan view of the pneumatic action detached and partly broken away; and

Fig. 4 is a bottom view of a part of the pneumatic player action.

In the practice of my invention, the piano action A can be, for the most part, of the usual type, although various changes may be made in this respect. In the embodiment illustrated, I have shown the ordinary form 75 of piano action unit, comprising a hammer 10 for striking the string 11, pivoted at 12 to the rail 13, from which is pivotally supported at 14 the customary wippen 15, carrying the usual pivoted hammer jack 16 80 and other parts which I have not considered it necessary to illustrate. Pivoted to the wippen 15 near the outer end thereof at 17 is the customary sticker or abstract 18. All of these parts, as shown, are of the usual 85 construction.

Extending across the front of the piano, in front of the piano action above the key-board (not shown) is a pneumatic player action, designated by reference character B. 90 This pneumatic action B, or more accurately this upper player action—there being a so-called lower action (not shown) comprising pedal operated exhausting apparatus, etc., located beneath the key-board—comprises 95 a wind chest 19 connected at one end by the

duct 20 with the pressure reducing apparatus, a plurality of striker pneumatics 21, 22, for actuating the respective units of the piano action A, and a plurality of valves 5 23 in the wind chest for controlling the operation of the pneumatics. The valves 23 are mounted within the elongated block 28, the rear of which is closed by the diaphragm board 27, and these valves are controlled 10 from the usual tracker bar 24, illustrated diagrammatically in Fig. 1, the openings of the tracker bar being connected by means of tubes 26, 26^a and suitable passages within the block 29 to the chambered diaphragm board 27.

This player action mechanism just referred to and designated generally by the reference character B in Fig. 1 is not specifically described or claimed in this application, as the subject matter is fully disclosed and claimed in my copending application Serial No. 230,417, filed April 24, 1918, of which the present application is a division.

The pneumatics 21, 22 are collapsed by the 25 admission of air to the action through the perforations in the music sheet and the holes in the tracker bar, in a manner more particularly described in my co-pending application above mentioned. As the pneumatics collapse, their lower movable parts or leaves are raised, and this movement is transmitted to the corresponding units of the piano action A, in such a manner that the strings are properly struck by the hammers. For this purpose, each of the stickers or abstracts 18 of the piano action is adapted to be actuated by a rigid striker on the corresponding pneumatic. Each of the upper pneumatics, in the form shown, has a small, 30 rigid striker constituted by a cleat or striker arm 55 rigidly secured by a screw 56 to the under surface of the movable leaf of the pneumatic at the rear of said leaf. A part of the cleat extends rearwardly beyond the leaf and under a button 57 carried by a bracket 58 that is rigidly secured by a screw 59 or the like to the front edge of the corresponding sticker 18. The button 57 has a layer of felt 57^a on its lower surface, adapted to 35 be struck by a striker or cleat 55. The brackets 58 are secured to and are a part of the piano action as distinguished from the player action, the elements referred to by the terms "piano action" and "player action" having been designated by the letters A and B, respectively, and described in detail above. The normal position of the parts is shown in Fig. 1, from which it will be evident that as the upper pneumatic 21 is collapsed, the button 57 (and bracket rigidly secured thereto) will be raised, thereby carrying upward the sticker 18 to a sufficient extent to operate the hammer 10. The brackets 58 appurtenant to the pneumatics 22 of the lower tier 40 are arranged in line with those appurtenant

to the upper pneumatics, and the lower pneumatics are provided with rigid striker arms which extend up into coöperation with the corresponding brackets 58, it being understood that by preference the single line 70 of brackets will extend across the piano action approximately in line with the pneumatics of the upper tier, as shown, although changes may be made in this regard. The rigid strikers of the lower pneumatics 22 are 75 formed by cleats 55^a secured to the lower leaves of said pneumatics by screws 56 in substantially the same relation as the cleats 55, but the cleats 55^a are provided with rigid upward extensions 55^b, located adjacent 80 the rear ends of pneumatics 22 and presenting rigid finger-like members which extend at their upper ends into the spaces between the cleats or strikers 55 with which they alternate. The strikers of both the upper and lower tiers are preferably made of wood, and their upper striking surfaces, co-operating with the buttons 57, are preferably slightly curved, so as to make the most 85 advantageous striking contact with the buttons on the brackets 58. The buttons 57 are vertically adjustable, inasmuch as they are provided with threaded stems or shanks 57^b engaging threads in the respective wooden brackets. At their upper ends, the 90 threaded shanks are provided with manipulating heads 57^c, which enable them to be screwed up or down, i. e., toward or away from the coöperating rigid strikers 55 or 55^b. In this manner, a very nice adjustment of the player action can be obtained after the same has been installed in the piano case, and all lost motion between the 95 pneumatics and the corresponding strikers can be readily taken up, so that a fully effective actuation of the piano action unit by the corresponding player action unit will be insured. On the other hand, in order to prevent an upward movement of the striker beyond the extent required, a suitable stop 100 mechanism is provided. Preferably, this stop mechanism coöperates with the brackets 58 or parts thereof, and is in the form of a rail having a plurality of independently adjustable stop members. In the example 105 shown, a stop rail 60 extends across and in close abutting relation to the upper faces of the pneumatics 21 of the upper tier at the rear of said pneumatics and lengthwise of the piano. The rail 60 may be supported by 110 brackets 61 at the ends of the player action, as shown in Fig. 3, said brackets extending alongside the end pneumatics of the upper tier in parallel relation thereto and having their rear ends underlying the rail 60 and 115 secured thereto by screws 62. At their forward ends, the supporting brackets are preferably interposed and secured between the connecting rails 44, 47. The rail 60 carries a plurality of stops 63, preferably constituted 120

125 130

by buttons similar to the buttons 57, having threaded shanks 63^a engaging screw threaded openings in the stop rail and provided at their upper ends with manipulating heads 63^b. The rear part of the stop rail projects beyond the upper pneumatics, so as to overhang the same, and stops 63 are supported by the overhanging portion of the rail with the buttons below the stop rail and the manipulating heads 63^b above the same, where they are readily accessible. The brackets 58 on the stickers are preferably substantially L-shaped, the upper leg being attached to the sticker by the screw 59 and the lower leg carrying the adjustable striker contacting button 57. The lower leg of the bracket is preferably beveled at its upper face in a direction rearwardly and upwardly toward the sticker, and the corresponding stop button 63 on the stop rail is arranged in opposing relation, so that its lower felted surface 63^c is parallel to and opposes the beveled surface on the bracket slightly in front of the threaded stem 57^b. When the corresponding pneumatic is collapsed, the sticker is raised until the beveled surface of the bracket engages the under surface of the stop button, which can be adjusted by manipulation of the shank 63^a, so that the upward movement of the sticker is arrested at exactly the proper point.

It will be understood that by arranging all of the brackets 58 in one row, a single stop rail will suffice for limiting the movement of all the various piano action units actuated by the pneumatic player action, by reason of the coöperation of the stop rail with all of the brackets. Nevertheless, the striker mechanism, on the other hand, or, in other words, the means for striking the brackets, is of the very simplest construction, because the cleats rigidly applied to the upper pneumatics are of the simplest form and of very small size, while the cleats of the pneumatics of the lower series merely have to be equipped with a relatively small upper extension which, in the process of manufacture, can be readily applied to or formed integral with the main part of the cleat attached to the movable leaf. The brackets 58 will, of course, be attached to the stickers at the most convenient height, and the player action is thereby adapted to pianos of different heights.

The arrangement described is extremely compact, takes up very little room in the piano case, comprises very few parts, and yet provides a very nice adjustment. A minimum number of parts is interposed between each pneumatic and the corresponding piano action unit, and yet the provision for accurately controlling the operation of the stickers and the elements operated thereby is simple, efficient and generally satisfactory.

Various changes may be made in the details of the construction without departing from the scope of my invention as defined in the claims. It will be obvious, for example, that in certain broad aspects of the invention, it is not essential for the rigid strikers to engage brackets or other means on the stickers.

What I claim is:

1. In a player piano, piano action units including wippens and stickers, a wind chest in front of the same, tiers of pneumatics connected to said wind chest and extending rearwardly therefrom, means for collapsing said pneumatics, and striker members projecting rigidly from the movable leaves of the pneumatics of said tiers and having striking surfaces located in substantially a single line or series extending across the piano for contacting with said piano action units and thereby actuating the same.

2. In a player piano, a plurality of piano action units, each including a wippen and a sticker, a wind chest in front of said units, pneumatics operatively connected with said chest and extending rearwardly therefrom, said pneumatics arranged in different tiers, striker members rigid with the movable leaves of the pneumatics and mounted thereon at the rear ends thereof, and adjustable buttons carried by the piano action units all in one row and overlying said strikers so as to be lifted thereby when the pneumatics are collapsed, whereby said piano action units are actuated.

3. In a player piano, a plurality of piano action units, a wind chest in front of the same, pneumatics operatively connected with said wind chest and extending rearwardly therefrom, striker members rigid with movable leaves of said pneumatics, said pneumatics arranged in different tiers, and contact members on the respective piano action units adapted to be engaged by said strikers for actuating said units and all arranged in one tier.

4. In a player piano, a plurality of piano action units, a wind chest in front of the same, pneumatics arranged in tiers and extending rearwardly from said wind chest, striker members rigid with the movable leaves of the pneumatics, the striker members of the pneumatics of a lower tier having their striking surfaces in approximately the same horizontal plane as the striker members of the pneumatics of the upper tier, and contact members on the respective piano action units adapted to be engaged by the striker members.

5. In a player piano, a plurality of piano action units, a wind chest in front of the same, tiers of pneumatics operatively connected to said chest and extending rearwardly therefrom, striking projections extending rearwardly and rigidly from the

movable leaves of the pneumatics, and having striking surfaces located substantially in a single line extending across the piano to engage and actuate the respective piano action units.

6. In a player piano, a plurality of piano action units, a wind chest in front of the same, pneumatics projecting rearwardly from said wind chest and having their mov-

10 able leaves lowermost, said pneumatics arranged in different tiers, strikers attached to but rigid with the movable leaves of the pneumatics of said tiers at the rear ends thereof, said strikers having their striking surfaces all lying in substantially a single horizontal plane, and adjustable contact buttons engageable by said strikers and carried by the piano action units above the latter, said buttons all arranged in a single tier.

15 7. In a player piano, a plurality of piano action units, a wind chest in front of the same, pneumatics projecting rearwardly from said chest toward said units and ar-

20 ranged in upper and lower tiers, cleats rigid with the movable leaves of the pneumatics of said tiers, said cleats having striking surfaces all located substantially in one tier, and means on said piano action units adapted to be engaged by said striking sur-

25 faces for the actuation of said units.

8. In a player piano, a plurality of piano action units, a wind chest in front of the same, tiers of pneumatics operatively connected to said chest and extending rearwardly therefrom, striking projections extending rearwardly and rigidly from the movable leaves of the pneumatics, and having striking surfaces located substantially in a single horizontal line extending across

30 the piano to engage and actuate the respective piano action units, and adjustable means for taking up lost motion between said striking projections and the corresponding piano action units.

45 9. In a player piano, a plurality of piano action units, a wind chest in front of the same, tiers of pneumatics projecting rearwardly from said chest toward said unit, contact members rigid with the movable

50 leaves of the pneumatics of said tiers, the contact members of a lower tier having rigid upward extensions extending into a plane in which the contact members of the pneumatics of the upper tier are located,

55 means on said piano action units arranged in substantially a single tier for contact by said contact members, whereby said piano action units are actuated, and means for taking up lost motion between the contact mem-

60 bers on the pneumatics and the piano action units.

10. In a player piano, a plurality of piano action units each including a sticker, a wind chest in front of said units, pneumatics operatively connected with said wind

chest and extending rearwardly therefrom and arranged in upper and lower tiers, brackets on said stickers arranged in a single tier, adjustable buttons on said brackets, and striker members rigid with and mounted on the movable leaves of said pneumatics adapted to engage said buttons.

11. In a player piano, a plurality of piano action units including wippens and stickers, a wind chest in front of the same, tiers of pneumatics extending rearwardly from said wind chest, contact members on said piano action units located in substantially a single line or series extending across the piano for presenting contact surfaces whereby the piano action units are actuated, and striker members carried rigidly by the movable leaves of the pneumatics of said tiers, and having striking parts all located in substantially a single line or series for engagement with said contact surfaces.

12. In a player piano, a plurality of piano action units including wippens and stickers, a wind chest in front of the same, tiers of pneumatics extending rearwardly from said wind chest, contact members on said piano action units located in substantially a single line or series extending across the piano for presenting contact surfaces whereby the piano action units are actuated, and striker members carried rigidly by the movable leaves of the pneumatics of said tiers, and having striking parts all located in substantially a single line or series for engagement with said contact surfaces, and means for adjusting relatively to each other the striking surfaces of the rigid strikers of the pneumatics of said tiers, and the contact surfaces of the corresponding piano action units.

13. In a player piano, a plurality of piano action units, a pneumatic player action for actuating the same including player pneumatics, and means carried by and forming an integral part of the said player action for limiting the movement of said piano action units by said player action, said means lying closely adjacent the fixed leaves of the player pneumatics.

14. In a player action, a plurality of piano action units, a pneumatic player action for actuating the same including player pneumatics, and stop means secured to and forming a part of said player action to engage said piano action units directly and thereby restrict the movement of the same, said stop means lying closely adjacent the fixed leaves of the player pneumatics.

15. In a player piano, a plurality of piano action units, a pneumatic player action for actuating the same including player pneumatics, and means including a stop rail forming a part of said player action and extending across the latter, for limiting the movement of said piano action units, said

stop rail abutting the fixed leaves of the player pneumatics.

16. In a player piano, a piano action including wippens and stickers, a player action having tiers of pneumatics, means on said stickers arranged in a single series and engaged by said player action for actuating the piano action, and means connected to and forming part of said player action extending across the piano in proximity to said engaged means to limit the operation of the piano action units.

17. In a player piano, a plurality of piano action units including stickers, a pneumatic player action having tiers of pneumatics, brackets on said stickers arranged in a single series, means for actuating said piano action units from said player action by lifting said brackets and a stop device on said player action coöperating with said brackets to limit the movement of said piano action units.

18. In a player piano, a plurality of piano action units including wippens and stickers, a pneumatic player action including tiers of pneumatics, brackets on said stickers arranged in substantially a single line or series across the piano, striking means operable from the pneumatics of said tiers for lifting said brackets and thereby said stickers, and means including a stop rail connected to and forming part of said player action and extending across said brackets to be engaged thereby so as to limit the operation of said piano action units.

19. In a player piano, a plurality of piano action units, a player action including tiers of pneumatics, means including a single series of adjustable contact buttons having their contact surfaces lowermost for imparting the movement of the pneumatics of said tiers to said piano action units, said contact buttons having adjusting shanks with upwardly disposed manipulating heads which are accessible from above when the player action is in place in the piano, and means including adjustable stop buttons located in front of said contact buttons for limiting the operation of said pneumatics independently of said contact buttons, said stop buttons having shanks with manipulating heads similar and in proximity to the manipulating heads of the contact buttons.

20. In a player piano, a piano action, a player action including player pneumatics, and means attached to and forming part of said player action and extending across the piano in front of the units of the piano action to limit the operation of said units, said means abutting the fixed leaves of the player pneumatics.

21. In a player piano, a plurality of piano action units including stickers, a wind chest in front of said units, pneumatics arranged in upper and lower tiers extending rear-

wardly from said wind chest, striker members rigid with the movable leaves of the pneumatics of said tiers, the striker members of the pneumatics of the lower tier having their striking surfaces in substantially the same horizontal plane as the striking surfaces of the striker members of the pneumatics of the upper tier, and bracket members attached to the stickers of the piano action units, all in one tier, and adapted to be engaged by said striking surfaces.

22. In a player piano, a plurality of piano action units including stickers, brackets on said stickers, a player action including player pneumatics having means to engage said brackets for actuating the piano action, and a stop rail attached to and forming part of said player action above said brackets in close proximity to the fixed leaves of said player pneumatics and adapted to be engaged by said brackets for limiting the movement of the stickers.

23. In a player piano, a piano action, a player action for operating the same, comprising a plurality of pneumatics arranged in tiers, and a stop member extending across and in close proximity to the pneumatics of the upper tier and disposed slightly rearwardly thereof for engagement by the piano action units whereby the movement of said piano action units by means of the pneumatics is limited.

24. In a player piano, a plurality of piano action units, a wind chest in front of the same, pneumatics arranged in tiers and extending rearwardly from said wind chest, striker members rigid with the movable leaves of said pneumatics, the striker members of the lower tier having their striking surfaces located in substantially the same horizontal plane as the striking surfaces of the striker members of the upper tier, contact members on said piano action units adapted to be engaged by said striking surfaces, and a stop member secured to and forming a part of the player action and located above the pneumatics of the upper tier for engagement by the piano action units whereby the movement of the piano action units by the pneumatics is limited.

25. A pneumatic player action, for operating the piano action of a player piano, including striker pneumatics arranged in a plurality of tiers, arms rigidly secured to the movable leaves of said striker pneumatics, said arms being provided with striking surfaces, the striking surfaces of the arms of the different tiers all normally lying in a horizontal plane.

26. A pneumatic player action for operating the piano action of a player piano, including striker pneumatics arranged in a plurality of tiers, striker arms engaging and rigidly secured directly to the movable leaves of said striker pneumatics, said arms being

provided with striking surfaces, the striking surfaces of the arms of the different tiers all normally lying in a horizontal plane.

27. A striker arm, for attachment to the movable leaf of a striker pneumatic comprising a substantially horizontal portion for engagement with the pneumatic and an integral vertically extending portion contacting directly with a part of a piano action unit.

28. A striker arm, for attachment to the movable leaf of a striker pneumatic, comprising a portion for engagement with the pneumatic and an integral upwardly extending portion contacting directly with a part 15 of a piano action unit.

In witness whereof, I have hereunto set my hand on the 31 day of July, 1919.

STANLEY L. FISHER.
